CLAIM

The ornamental design for a floodlight projector, as shown and described.

DESCRIPTION

2. Floodlight projector

3. Floodlight projector

FIG. 2.1 is a front view of an embodiment of the floodlight projector;

FIG. 2.2 is a rear view thereof;

FIG. 2.3 is a left-side view thereof;

FIG. 2.4 is a right-side view thereof;

FIG. 2.5 is a top, rear and right-side perspective view thereof;

FIG. 2.6 is a top, front and right-side perspective view thereof; and

FIG. 2.7 is a top view thereof.

FIG. 3.1 is a front view of another embodiment of the floodlight projector;

FIG. 3.2 is a rear view thereof;

FIG. 3.3 is a right-side view thereof;

FIG. 3.4 is a left-side view thereof;

FIG. 3.5 is a top view thereof;

FIG. 3.6 is a top, rear and right-side perspective view thereof; and

(Continued)

FIG. 3.7 is a top, front and right-side perspective view thereof.
